UNITED STATES PATENT OFFICE.

JOHN PHILLIPS, OF CHICAGO, ILLINOIS.

SQUARE.

SPECIFICATION forming part of Letters Patent No. 710,509, dated October 7, 1902.

Application filed March 10, 1902. Serial No. 97,433. (No model.)

To all whom it may concern:

Be it known that I, JOHN PHILLIPS, a citizen of the United States, residing at Chicago, in the county of Cook and State of Illinois, have 5 invented certain new and useful Improvements in Squares; and I do hereby declare the following to be a full, clear, and exact description of the invention, such as will enable others skilled in the art to which it appertains 10 to make and use the same, reference being had to the accompanying drawings, and to the figures of reference marked thereon, which form a part of this specification.

This invention relates to squares, and particularly to folding steel squares.

The object of the invention is to form an improved square which can be readily disconnected and folded to be carried in a carpenter's box.

20 A further object is to form an improved joint between the parts which will hold them rigidly together in true position for use.

The invention is illustrated in the accompanying drawings, in which—

25 Figure 1 is a perspective view of the square, parts being broken away. Fig. 2 is a section on the line 2 2 of Fig. 1. Fig. 3 is a face view of one of the arms detached, and Fig. 4 is an edge view of the same. Fig. 5 is a face view 30 of the other arm detached, and Fig. 6 is a section on the line 6 6 thereof.

The arms (indicated at 6 and 7) are joined together by a lap-joint formed by halving the ends of the arms and beveling the laps, as indicated at 8. Furthermore, a mortise-and-tenon joint is formed to more rigidly retain the arms together. This is done by making or leaving a tenon 9 on the lap of the arm 6, and the top of this tenon is flush with the face 40 of the arm. A mortise 10 is formed in the lap of the arm 7 to receive the tenon. The edges of the tenon and mortise are beveled, as at 11, which forms a better fitting joint when the parts are clamped together than would otherwise be the case.

45 A boss 12 is formed on the tenon, and a

threaded bore is formed in the boss and arm to receive a thumb-screw 13, the head of which is recessed, as at 14, to receive the boss and to form a rim 15, which contacts with the lap 50 of the arm 7.

When it is desired to fold the square, the thumb-screw is taken out or withdrawn a sufficient distance to allow the joint to be broken and the arms turned into parallelism. The 55 arms can then be clamped by the thumb-screw to obviate the danger of loss of any of the parts. When it is desired to use the square, the joint is made and clamped in an obvious manner.

Having thus described the invention, what I claim as new, and desire to secure by Letters Patent, is—

1. A square comprising two arms joined by a lap-joint at their ends, the laps being interlocked by an angular mortise in one of the laps and a corresponding tenon integral with the other.

2. A square comprising two arms lapped at the ends, said arms having an interlocking 70 angular mortise and tenon, and a thumb-screw engaging the arms to clamp the same together.

3. A square comprising two separable arms the ends of which are joined by a lap-joint 75 and angular mortise and tenon, the edges of the mortise and tenon being beveled, and means to clamp the arms together at said ends.

4. A square comprising two arms lapped at the ends, one of said arms having an angular 80 tenon and the other a corresponding mortise therethrough to receive said tenon, and a binding-screw engaging the tenon, said screw having a head projecting beyond the edge of the tenon and engaging the arm having the 85 mortise.

In testimony whereof I affix my signature in presence of two witnesses.

JOHN PHILLIPS.
